UNITED STATES PATENT OFFICE

146,240

DESIGN FOR AN AIRPLANE

Frank A. Wedberg, Buffalo, and Frederick I. Steele, Snyder, N. Y., assignors to Curtiss-Wright Corporation, a corporation of Delaware

Application April 7, 1945, Serial No. 119,368

Term of patent 3½ years

(Cl. D71—1)

To all whom it may concern:

Be it known that we, Frank A. Wedberg and Frederick I. Steele, citizens of the United States residing, respectively, in Buffalo and Snyder, both in the county of Erie and State of New York, have invented a new, original, and ornamental Design for Airplanes, of which the following is a specification, reference being had to the accompanying drawings, forming a part thereof.

This application is a continuation-in-part of our copending application, Serial Number D-113-884, filed June 6, 1944.

Figure 1 is a top plan view of an airplane showing our new design;

Figure 2 is a side elevational view thereof;

Figure 3 is a front elevational view, with parts

of the propellers broken away for clarity in illustration;

Figure 4 is a perspective view taken from the front, below and to the side of the longitudinal axis of the airplane and with the propeller blades omitted as they are substantially invisible when the aircraft is in flight; and

Figure 5 is also a perspective view taken from the front, below and to the side of the longitudinal axis of the airplane, with the landing gearing extended and the wings folded.

We claim:

The ornamental design for an airplane, as shown.

FRANK A. WEDBERG.
FREDERICK I. STEELE.
